(57) **CLAIM**

The ornamental design of crimping pliers, as shown and described.

DESCRIPTION

FIG. 1 is a perspective view showing my new crimping pliers with opened handle and for an additional actuation mechanism at the top of the pliers head in an open state;

FIG. 2 is a front side view thereof;

FIG. 3 is a right side view thereof;

FIG. 4 is a rear view thereof;

FIG. 5 is a left side view thereof;

FIG. 6 is a top view thereof;

FIG. 7 is the bottom view thereof;

FIG. 8 is a perspective view showing my new crimping pliers, wherein the handles are in an open operating state and the additional actuation mechanism is in a closed state;

FIG. 9 is a front side view thereof;

FIG. 10 is a right side view thereof;

FIG. 11 is a rear view thereof;

FIG. 12 is a left side view thereof;

FIG. 13 is a top view thereof;

FIG. 14 is the bottom view thereof;

FIG. 15 is a perspective view showing my new crimping pliers, wherein the handles are in a closed operating state and the additional actuation mechanism is in an open state;

FIG. 16 is a front side view thereof;

FIG. 17 is a right side view thereof;

FIG. 18 is a rear view thereof;

FIG. 19 is a left side view thereof;

FIG. 20 is a top view thereof; and,

FIG. 21 is the bottom view thereof.

The broken lines illustrate portions of the crimping pliers which form no part of the claimed design.
